UNITED STATES PATENT OFFICE.

EDMUND C. BROWN, OF HARDIN, MONTANA.

WASHING MACHINE.

Application filed May 12, 1921. Serial No. 468,568.

To all whom it may concern:

Be it known that I, EDMUND C. BROWN, a citizen of the United States, residing at Hardin, in the county of Big Horn and 5 State of Montana, have invented a new and useful Washing Machine, of which the following is a specification.

The device forming the subject matter of this application is a washing machine, and 10 the invention aims to provide novel means for imparting motion to the beaters, so that the same will be peculiarly efficient in removing the dirt from clothes without, however, tearing or injuring the clothes.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 the scope of what is claimed, changes in the precise embodiment of the invention shown can be made without departing from the spirit of the invention.

In the drawings:—

30 Figure 1 shows in vertical section, a device constructed in accordance with the invention, parts appearing in elevation; Figure 2 is a section through the receptacle and attendant parts, the cutting plane in Figure 35 2 being at right angles to the cutting plane in Figure 1; and Figure 3 is a top plan of the receptacle and attendant parts, portions being broken away.

In carrying out the invention there is provided a receptacle 1 including a side wall 2, a corrugated bottom 3, and a top 4.

The numeral 5 denotes a U-shaped hanger, including a long arm 6 and a short arm 7. The long arm 6 of the hanger 5 is secured 45 to the top 4 of the receptacle, the hanger extending outwardly to the side wall 2, as clearly shown in Figure 2. A bearing block 8 is located in the hanger 5 and is secured to the arm 5' of the hanger.

50 Bearing posts 9 are secured to the outer surface of the side wall 2 of the receptacle 1, and form part of a frame 10 whereon the receptacle 1 is supported. The frame 10 carries a motor 11.

55 The outer ends of shafts 12 are journaled in the bearing posts 9, the inner ends of the

shafts being journaled in the bearing 8 and in the parts 6 and 7 of the hanger 5. The inner ends of the shafts 12 are connected operatively by intermeshing gear wheels 14, 60 located on the shafts, and disposed between the bearing 8 and the arm 7 of the hanger 5. Intermediate their ends, the shafts are supplied with cranks 15. Any suitable means may be provided for connecting one of the 65 shafts operatively with the motor 11. In the present instance, a driving connection is secured, at the point alluded to, by a belt, shown at 22.

Rock shafts 16 are provided, the outer 70 ends of the rock shafts being journaled in the side wall 2 of the receptacle 1, the inner ends of the rock shafts being journaled in the part 6 of the hanger 5. Beaters 17 are shown. Pitmans 18 are pivoted, each, at 75 one end, to one of the cranks 15, the other end of each pitman being pivoted to the corresponding beater 17. Retractile springs 24 are provided, the springs being connected at one end to the pitmans 18, and being connected, at their other ends, to the beaters 17. Arms 19 are pivoted to the upper ends of the beaters 17. The rear ends of the arms 19 are mounted for reciprocation in the rock shafts 16. The ends 19 have shoulders 20. Compression springs 21 surround portions of the arms 19 and abut against the shoulders 20 and against the rock shafts 16.

In practical operation, when motion is 90 transmitted to one of the shafts 12, through the instrumentality of the motor 11 and the belt 22, or otherwise, motion will be transmitted from the said shaft 12 to the other shaft 12 through the gear wheels 14. 95 The cranks 15 and the pitmans 18 operate the beaters 17, the arms 19 controlling and pressing down the beaters. The beaters 17 have a combined orbital and swinging movement, and have a pounding and drawing 100 action on the garment. The garment is urged transversely of the corrugations in the bottom 3 of the receptacle 1. One garment is moved away from another, thereby exposing all parts of the garments to the action of the cleaning fluid and the beaters. 105

The springs 21 permit the beaters 17 to yield slightly, thereby preventing a tearing of the garments which are being washed. The springs 24 restore the beaters to normal position after the beaters have yielded to an obstruction of any kind. The gear

wheels 14 produce a reverse motion in one side of the shafts 12 and the beaters 17, thereby bringing about a rotary motion of the contents of the receptacle 1 and obviating the necessity of reversing the direction of drive in the power plant. As a consequence, the operator may run the machine continuously in either direction, with equally good results.

Having thus described the invention, what is claimed is:—

1. In a device of the class described, a shaft supported for rotation and having a crank; a rock shaft supported for rotation; a beater; a pitman forming an angle with the beater, the pitman being connected at one end to the crank and at the other end to the beater; a retractile spring connected at its ends to the pitman and to the beater 20 and extending across the angle formed by

the pitman and the beater; an arm pivoted to the beater; and means for supporting the arm for swinging movement.

2. In a device of the class described, a crank shaft supported for rotation; a rock 25 shaft; a beater; a pitman forming a connection between the intermediate portion of the beater and the crank shaft; an arm pivoted to the upper end of the beater and slideable in the rock shaft; and spring means for resisting the sliding movement of the arm in the rock shaft, thereby to press the beater downwardly.

In testimony that I claim the foregoing as my own, I have hereunto affixed my signature in the presence of two witnesses.

EDMUND C. BROWN.
